(57) **CLAIM**

I claim the ornamental design for a network camera, as shown and described.

DESCRIPTION

FIG. 1 is a top perspective view of a network camera of the present invention;

FIG. 2 is a front view thereof;

FIG. 3 is a rear view thereof;

FIG. 4 is a side view thereof;
FIG. 5 is a side view thereof, opposite of that shown in FIG. 4;

FIG. 6 is a top view thereof; and,

FIG. 7 is a bottom view thereof.

The broken line showing of network camera is included for the purpose of illustrating environment and forms no part of the claimed design.
